UNITED STATES PATENT OFFICE

2,161,203

HAIR WAVING DEVICE

Floyd V. Schleimer, San Francisco, Calif., assignor to United States Appliance Corporation, San Francisco, Calif., a corporation of California

Application March 29, 1937, Serial No. 133,533

5 Claims. (Cl. 132—36)

This invention relates generally to devices used in the permanent waving of human hair, and more particularly it is concerned with the construction of devices used to supply heat, for the steaming operation.

In the permanent waving of hair it has become relatively common to use so-called heaters, which are clipped over the wound hair, for the steaming operation. Of more recent years so-called pre-heating equipment has come into usage, that is, equipment of the kind disclosed and claimed in Patent No. 1,972,186, granted September 4, 1934. Such equipment makes use of a so-called pre-heating apparatus, together with heat storage devices which are heated up to a predetermined temperature and then applied to the wound hair.

In the operation of pre-heating equipment I have found that there is a serious tendency for the handles of the heat storage devices to be heated to relatively high temperatures. Frequently the temperatures reached are such as to make the devices unsafe to be handled by an operator. In this connection it should be noted that frequently the heat storage devices are permitted to remain clipped upon the pre-heater for considerable periods of time, during which the handles are heated not only by conduction, but also by convection currents of air. Even though the temperature attained by the handles may not be such as to burn the skin, any unpleasant temperature increases the possibility of accidental burning of the subject. Another difficulty which has been experienced has been the attainment of a proper heat storage capacity, in the heat storage devices, without making the devices bulky in size.

It is an object of the invention to provide a heat storage device having improved finger gripping surfaces which will not be heated to unsafe or unpleasant temperatures.

A further object of the invention is to provide a heat storage device capable of adequate heat storage capacity, without being bulky in size.

45 Further objects of the invention will appear from the following description in which the preferred embodiment of the invention has been set forth in detail in conjunction with the accompanying drawing.

50 Referring to the drawing:

Fig. 1 is a side elevational view, illustrating a heat storage device in accordance with the present invention, applied to a protector and curler assembly.

55 Fig. 2 is a view showing the same device as in

Fig. 1, but looking towards the end of the device.

Fig. 3 is a bottom plane view of the heat storage device.

Fig. 4 is a cross-sectional detail taken along the line 4—4 of Fig. 1, on an enlarged scale.

Fig. 5 is a cross-sectional view taken along the line 5—5 of Fig. 4, and on the same enlarged scale.

The device as illustrated in the drawing consists generally of a pair of duplicate heat storage 10 elements 10, which are attached to a mounting 11, whereby the elements can be moved toward or away from each other. Also attached to the mounting 11 are the handles 12, which carry the finger grip pads 13.

15 The elements 10 are made of some suitable metal or metal alloy, which will afford a fairly high specific heat without being unduly heavy, as for example an aluminum or magnesium alloy. The inner opposed faces 14 are concave, while 20 the outer faces are generally convex.

25 The mounting 11 consists of a pair of yoke-like arms 16, which are pivotally connected by pin 17. A spring 18 serves to urge together the elements 10, with sufficient force to retain the 25 device upon a curler or upon the heating element of pre-heated apparatus. The branches or portions 16a of each arm 16, are shown attached to the associated heat storage element by means of rivets 19. The space directly between arm portion 30 16a, is occupied by a bulge 21, whereby the heat storage capacity is increased, without materially increasing the lateral dimensioning of the device.

35 The handles 12 are formed of suitable molded insulating material, such as Bakelite, or some equally effective synthetic resin product. The handles are attached to the arms 16 by suitable means such as rivets 22.

40 The pads 13 are preferably formed of resilient vulcanized rubber, with a cloth or felt surfacing 23 formed as an integral part of the same. In order to attach these pads to the handles, each pad is shown provided with a pair of integral studs 24, with the ends of these studs being provided with enlarged heads 26. The handle in turn is provided with openings 27, through which the studs 24 can be forced, to provide an adequate and convenient attachment.

45 In general my device is utilized in the same 50 manner as the heat storage devices disclosed in the above-mentioned Patent No. 1,972,186. In Figs. 1 and 2 the device is shown clipped upon the curler of a protector curler assembly 20, for a steaming operation. The bulge construction of 55

the heat storage elements 10 provides a maximum of heat storage capacity, without unduly increasing the lateral dimensioning of the device. The handles 12 of insulating material are relatively 5 poor conductors of heat, and in practice these handles will not conduct sufficient heat to the pads 13 to occasion disintegration of the vulcanized rubber. The rubber pads 13 are likewise relatively poor conductors of heat, so that as 10 a net result, the surfaces 23 can at all times be gripped by the operator, without burning or without affording an unpleasant sensation of heat. In addition to affording a relatively cool gripping surface, the cloth surfacing 23 provides an 15 adequate grip for the fingers of the operator, even though they may become wet with hair waving solution or oil.

I claim:

1. A heat storage device for the permanent waving of hair, comprising a pair of opposed heat storage members, a mounting for hingedly connecting said members together, a pair of handles of molded insulating material secured to said mounting whereby said elements can be swung 20 apart by pressing said handles together, and pads of resilient vulcanized rubber secured to said handles and forming finger-gripping surfaces, the outer faces of said pads having a covering of felt.
2. A device for the permanent waving of hair, comprising a pair of opposed elements adapted to 25 apply heat to wound hair, a mounting for hingedly connecting said elements together, a pair of handles formed of molded insulating material, said handles being secured to said mounting whereby said elements can be swung apart by pressing said handles together, pads of resilient vulcanized rubber secured to said handles and forming finger-gripping surfaces, said pads being retained upon said handles by studs formed integral with 30 said pads and extending through openings formed in said handles.
3. A device for the permanent waving of hair, comprising a pair of opposed elements adapted to 35

apply heat to wound hair, a mounting for hingedly connecting said elements together, a pair of handles formed of molded insulating material secured to said mounting, whereby said elements can be forced apart by pressing said handles together, and pads of resilient vulcanized rubber secured to said handles and forming finger-gripping surfaces, said pads being retained to said handles by studs formed integral with the pads and extending through openings formed in the 10 handles, the outer faces of said pads having a surface facing of felt. 5

4. A heat storage device for the permanent waving of hair, comprising a pair of elongated heat storage elements, the opposed inner faces of 15 said elements being concave, a mounting serving to hingedly connect said elements together, said mounting including a pair of arms with each arm having two points of attachment to its associated heat storage element, the points of attachment 20 being near the ends of the element and on the outer side of the same, each of said elements being formed of a solid mass of metal with more of the metal being distributed in the medial region of each element, than at the ends thereof. 25

5. A heat storage device for the permanent waving of hair, comprising a pair of elongated heat storage elements, a mounting for hingedly connecting said elements together whereby said elements are retained in parallel relationship, the 30 inner faces of said elements being concave to enable application to wound hair, said mounting including a pair of yoke-like arms, the two branches of each arm having points of connection to an associated heat storage element at points 35 near the ends of the element, said elements being formed of a mass of metal in which heat can be stored, the outer side of each of said elements being bulged outwardly in a region between the two points of connection, thereby affording 40 added heat storage capacity. 35

FLOYD V. SCHLEIMER.
